PULL-OUT SWITCH BLOCK

Jacob W. Dowler, Philadelphia, Pa., assignor to
 Heinemann Electric Company, Trenton, N. J.,
 a corporation of Pennsylvania

Application March 27, 1935, Serial No. 13,211

6 Claims. (Cl. 200—114)

My invention is an improved pull-out switch block having a reversible cover or closure for a base and permitting the making or the breaking of the circuit or circuits through the switch block while shielding the operative from danger at all times and insuring that the closure is securely held on the base in either the circuit making or the circuit breaking position.

In the preferred embodiment of my improvements the base contains one or more chambers each having therein a line contact and a load contact which are each housed between an insulating wall and a shielding contact. The shielding contacts are "dead" when the cover is removed, and are preferably electrically connected with spring fuse clips for the engagement of a fuse or fuses carried by the closure. The closure is also provided with contacts which, in one position of the closure, establish conducting relation between the respective line and load contacts and their respective shielding contacts, and through the fuse clips and fuses establish conductance between the line contact and the load contact. In the reverse position of the closure, the contacts carried thereby are free from engagement with the line contacts or load contacts, but in both positions the spring clips firmly grip the fuse so as to hold the cover securely in place upon the base.

The characteristic features and advantages of my improvements will further appear from the following description and the accompanying drawings in illustration thereof.

In the drawings, Fig. 1 is a top plan view of the base of my improved pull-out switch block with the cover contacts in place to connect the line terminals and load terminals with their respective shielding contacts; Fig. 2 is an irregular transverse sectional view of my improved device with the cover in place; Fig. 3 is a detached exploded view showing the relationship of a line contact, a shielding contact therefor, the insulation between them, and a fuse clip; Fig. 3a is a top plan view of the assembly shown in Fig. 3; Fig. 4 is a longitudinal sectional view through the device shown in Fig. 2 with the fuse omitted for greater clarity; Fig. 5 is a side elevation of a detached closure, with the fuse omitted for greater clarity of illustration; Fig. 6 is a bottom plan view of the closure shown in Fig. 5; and Fig. 7 is a transverse view taken on the line 7—7 of Fig. 5.

In the embodiment of my invention illustrated in the drawings, an insulating base member 1 is provided with the side walls 2 and 2', the end

walls 3 and 3' and with the partition wall sections 4 and 4' forming the chambers 5 and 5'. Tubular line terminals 6 and 6' are provided with conductor-clamping screws 7 and 7' and with conducting flat shanks 8 and 8' which are inserted through slots 9 and 9' in the end wall 3 and are secured by the screws 10 and 10' to conducting plates 11, 11' in the bottoms of the chambers 5 and 5' (Fig. 4).

The conducting plates 11, 11' have extensions 12 and 12' disposed angularly thereto and having up-bent ends 13 and 13' forming contact blades adjacent to opposite sides of the wall 4 and partly housed in recesses 14 and 14' in such wall section. Each of the plates 11, 11' contains an aperture for the passage of an insulating collar 15 and has superposed thereon an insulating spacer 16 having upturned edges 16' and electrically separating the plates 11, 11' and extensions 12, 12' from the bases 17, 17' of angular contact members provided with up-bent ends 18, 18' which lie parallel to the contact blades 13, 13' and shield the latter against being accidentally touched when the chambers 5, 5' are uncovered. Fuse clips 20, 20' are seated on the members 17, 17'. Bolts 21, 21' pass through apertures 22, 22' in the base 1 and through the collars 15, spacers 16, contacts 17, 17' and clips 20, 20', and have threaded thereon the nuts 23, 23' to hold the parts in fixed relationship to one another and to the base without any electrical contact between the fuse clips 20, 20' and the line contacts 13, 13', and without any electrical contact between the shielding contacts 18, 18' and the line contacts 13, 13'.

The members 12 and 12' and the members 17 and 17' are so shaped that the line contacts 13, 13' and the shielding contacts 18, 18' lie close to the inner end of the insulating partition wall 4 and are spaced a considerable distance from the end wall 3.

At the opposite ends of the block 1, tubular load terminals 6a and 6b, provided with clamping screws 7a and 7b, have shanks 8a and 8b inserted through slots 9a and 9b in the wall 3'. The shanks 8a and 8b are secured by screws 10a and 10b to conducting plates 11a and 11b in the bottoms of the chambers 5 and 5' (Fig. 4).

The conducting plates 11a have angularly disposed extensions 12a and 12b terminating in up-bent ends forming contact blades 13a and 13b partly housed in recesses 14a and 14b formed in the opposite sides of the insulating partition wall section 4'. The plates 11a and 11b contain apertures for insulating collars 15 and have su-

superposed thereon insulating spacers 16 which support the conducting plates 17a and 17b, which are so shaped that their up-bent ends 18a and 18b lie parallel with and shield the contact blades 13a and 13b. Spring fuse clips 20a and 20b have their bases seated on the insulating spacers 16 and screws 21a and 21b pass through the apertures 22a and 22b, through the collars 15, insulators 16, conductors 17a and 17b and fuse clips 20a and 20b into threaded engagement with nuts 23a and 23b to clamp the parts together.

The side wall 2 has the tapering walls 2a projecting inwardly therefrom and the wall 2' has the tapering walls 2b projecting inwardly therefrom to form guideways, 24, 24' midway the lengths of the walls 2 and 2'.

A cover or closure 25 of insulating material is provided with a drop pull handle 26 and is of such size as to overlap the inner edges of the walls 2, 2', 3, 3' when centered over the base member. A pair of insulating diaphragms 27 are secured to the inner face of the cover 25 transversely of the length thereof and have formed therein curved seats 28 (Fig. 7) for the engagement of cartridge fuses 29 and projecting tongues 30 adapted to be positioned in the guideways 24 and 24'.

A pair of fingers 31, 31' (Fig. 6) of insulating material, depend from the cover 25 adjacent to the diaphragms 27 and contacts 32, 32' are inserted in slots in the fingers 31, 31' and riveted to the respective fingers so as to form connected contacts on each side thereof.

A second pair of fingers 33, 33' of insulating material depend from the cover 25 adjacent to an end thereof, the fingers 33 and 33' being spaced from the diaphragms 27. Contacts 34, 34' are inserted in slots in the fingers 33, 33' and are riveted thereto to form connected contacts on each side of the respective fingers.

The fuse clips and fuses are symmetrically positioned relative to center lines of the structure so that the fuses engage and are held by the clips regardless of whether the cover 25 is applied to the base in the manner illustrated in Fig. 4, or in the reverse position thereto. The contacts, however, are so positioned in the base member and on the cover member that when the cover is applied to the base in the position shown in Fig. 4, the contact 32 enters between and electrically connects the contacts 13 and 18, the contact 32' enters between and electrically connects the contacts 13' and 18', the contact 34 enters between and electrically connects the contacts 13a and 18a, and the contact 34' enters between and electrically connects the contacts 13b and 18b.

In this position, current from the line contact 6 flows through the shank 8, plate 11, extension 12, contact 13, contact 32, contact 18, plate 17, clip 20, cartridge 29, clip 20a, plate 17a, contact 18a, contact 34, contact 13a, extension 12a, plate 11a, shank 8a, and terminals 6a to the load conductor.

Similarly current entering from a line conductor through the line terminal 6' passes through the shank 8', plate 11', extension 12', blade 13', contact 32', contact 18', plate 17', clip 20', fuse 29, clip 20b, plate 17b, contact 18b, contact 34', contact 13b, extension 12b, plate 11b, shank 8b, and load terminals 6b to the load conductor.

When, however, the cover 25 is applied to the base member in the reverse or upside down position from that shown, the contacts 34 and 34'

occupy the vacant spaces indicated by dotted lines (Fig. 1) between the wall 3 and the line contacts 13, 13'. The contacts 32, 32' then occupy the vacant spaces indicated by dotted lines between the inner end of the partition 4' and the load contacts 13a and 13b. Consequently there is no flow of current, notwithstanding the engagement of the fuses and the spring clips, owing to the fact that the gaps between the line contacts 13, 13' and their shielding contacts 18, 18' and the gaps between the load contacts 13a and 13b and their shielding contacts 18a and 18b are now open.

Having described my invention, I claim:

1. A pull-out switch block having a base member and a cover member, one of said members having connected therewith a fuse clip and a line terminal insulated from said fuse clip and the other of said members having connected therewith a fuse for engagement in said clip and means for connecting said fuse clip with said line terminal.

2. A pull-out switch block having a base member and a cover member, one of said members having fuse clips connected therewith and the other of said members having a fuse connected therewith for engagement with said fuse clips, a pair of contacts on one of said members offset from the respective fuse clips, and a pair of contacts on the other of said members adapted to engage said first named pair of contacts in one position of said cover member and to be free from engagement with said contacts in the reverse position of said cover member, said fuses engaging said clips and holding said cover member and base member together in both positions of said cover member.

3. A pull-out switch block having a base member and a cover member, one of said members having a fuse connected therewith and the other of said members having fuse clips for the engagement of said fuse, and contacts on the respective members which engage one another in one position of said cover member relatively to said base member and are disengaged from one another in another position of said cover member relative to said base member, said fuse and clips holding said members together in both the engaging and disengaging positions of said contacts.

4. A pull-out switch block comprising a base containing a chamber, a line contact and a load contact each having a base fixed to the bottom of such chamber, a shielding contact for said line and load contacts and having bases superposed above and insulated from the bases of said line contacts and load contacts, fuse clips connected with said shielding contacts, a closure for said chamber having thereon a contact movable into conducting relation with said line contact and its shielding contact and said closure having thereon a contact movable into conducting relation with said load contact and its shielding contact, said closure having connected therewith a fuse movable into conducting relation with said fuse clips.

5. A pull-out switch block comprising a base containing a plurality of chambers separated by insulating wall sections having a passage between the ends thereof, a line contact on each side of and shielded by one of said wall sections, a load contact on each side of and shielded by the other of said insulating wall sections, a shielding contact in front of, but electrically insulated from

each of said line contacts and load contacts, a fuse clip connected with each of said shielding contacts, a closure having a diaphragm transversely thereof and movable into said passage, fuses carried by said diaphragm and adapted for engagement with fuse clips aforesaid, and contacts carried by said closure and movable into conducting engagement with the respective line and load contacts and the complementary shielding contacts therefor in one position of said closure, said closure contacts being disengaged from the line and load contacts in the reverse position of said closure.

6. A pull-out switch block comprising a base containing a plurality of chambers separated by insulating wall sections having a passage between the ends thereof, a line contact on each side of and shielded by one of said wall sections, a load

contact on each side of and shielded by the other of said insulating wall sections, a shielding contact in front of, but electrically insulated from each of said line contacts and load contacts, a fuse clip connected with each of said shielding contacts, a closure having a diaphragm transversely thereof and movable into said passage, fuses carried by said diaphragm and adapted for engagement with said fuse clips aforesaid, and contacts carried by said closure and movable into conducting engagement with respective line and load contacts and the complementary shielding contacts thereof in one position of said closure, said closure contacts being disengaged from the line and load contacts in the reverse position of said closure, but said diaphragm adapted to lie in said passage in both positions of said closure. 5 10 15

JACOB W. DOWLER.
